Patented Mar. 1, 1921.

UNITED STATES PATENT OFFICE.

WILLIAM BERKMAN, OF CLEVELAND, OHIO.

LEVELING INSTRUMENT.

1,369,957.

Specification of Letters Patent.

Patented Mar. 1, 1921.

Application filed May 1, 1920. Serial No. 378,250.

To all whom it may concern:

Be it known that I, WILLIAM BERKMAN, a citizen of the United States, residing at Cleveland, in the county of Cuyahoga and 5 State of Ohio, have invented certain new and useful Improvements in Leveling Instruments, of which the following is a specification.

My improvement in leveling instruments 10 resides more particularly in the balancing index member and the mode of mounting it within the leveling bar; in the demountable sighting elements used with the bar; and in the mitering blade which is pivotally 15 seated within and at one end of the bar; all substantially as described and claimed, and as shown in the drawing accompanying this application, in which Figure 1 is a top plan view of my improved leveling instrument, and Fig. 2 is a side elevation thereof partly in section and showing a pair of sighting members mounted thereon. Fig. 3 is a bottom plan view of the instrument, and Fig. 4 is an enlarged cross section on line 25 4—4, Fig. 2. Figs. 5, 6 and 7 are perspective views of the three sections comprising the balancing index member, and Fig. 8 is a vertical section centrally through said sections assembled as in use.

30 The instrument comprises a rectangular level or bar 2 of wood having separate metal end plates 3 and 4 affixed to its opposite ends. The central portion of this bar has a round opening 5 extending transversely there- 35 through, and the outer ends of this opening at opposite sides of said bar are enlarged to provide retired flat seats 7 adapted to receive and hold two graduated glass disks 8 in parallel and axial alinement. These glass 40 disks are held firmly to their respective seats by rings of putty 9 or by any other suitable means adapted to be removed and replaced if the disks become broken and require repair. Each glass disk has a shallow conical 45 socket or cavity 10 centrally within its inner face or surface adapted to provide a glass bearing for short pointed trunnions on the opposite side edges of a flat tapering metal index blade 12. The opposite ends of 50 this blade taper to a sharp point and the central portion of the blade has parallel flat faces and a round opening therein situated below the axis as represented by trunnions 11. This blade is always held in a perpen- 55 dicular or upright position by a balancing spirit tube consisting of two tubular sections

13 and 14, each of which is closed at its outer end and open and screw threaded at its inner end. One tubular section has a reduced externally-threaded extension 15 and an annular seating shoulder 16, and the other section has an internally-threaded open end 17 with an end seating shoulder 18, whereby said sections may be screwed together with the index blade sleeved over extension 15 and tightly clamped between the respective shoulders on said sections, see Fig. 8. A fluid is placed within one of the sections before clamping the parts together and the index member thus built up is perfectly balanced and very sensitive and responsive in turning on its pivots in leveling operations, and the instrument can be used for leveling, mitering or establishing a plumb line through the agency of the index blade and 75 the graduations on either glass disk. The position of the index blade is visible at all times from either flat side of bar 2, and the sharp end edge of the index blade may also be viewed through a round opening 19 and 80 a glass disk 20 at the upper side edge of the bar. The simplicity of this arrangement of parts makes the instrument inexpensive to construct and to maintain in repair; the initial adjustment of the graduated glass 85 disks to their seats and a correct assembly of the parts is easily and quickly obtained; and the glass disks provide exceptionally sensitive bearings for the balancing index member and obviate the necessity of the use of 90 metal or other intervening bearing parts.

The instrument may also be used in establishing levels by sighting, and for that purpose the bar is provided with a metal-lined socket 21 in one edge near each end wherein 95 the short round stem 22 of a sighting element is adapted to be inserted. One sighting member 23 has a straight edge 24 and the other member 25 is cupped and has a small sight opening 26 centrally therein. 100 These sighting members may be bodily removed when not in use.

The instrument is further provided with a mitering blade 27 having a quadrant or rounded enlargement 28 at one end, and this 105 blade is adapted to be inclosed within a longitudinal recess 29 within one edge of bar 2 and to be clamped between ears 30 on one of the metal end plates 4 with the quadrant exposed to view. Gage marks on 110 the side of this quadrant extend tangential to its circular edge and are adapted to be

aligned with the end face of plate 4 when the blade is turned on its pivot clamping screw 31. When the blade is adjusted to any given or desired angle it is clamped against movement by rotating screw 31 by a nail or other instrument inserted within the opening 32 in the head of this screw. The mitering blade may also be set accurately at different angles to the straight edges of the level by the use of the balanced index blade and the graduated glass dials, and by their joint use it is an easy matter to correctly measure the angle between two diverging or converging surfaces or to establish and fix the angular relation between two parts which may or may not be joined together.

What I claim is:

2. A leveling instrument, comprising an index blade having trunnions and separate tubular balancing sections detachably secured thereto beneath the axis of said trunnions and adapted to contain a liquid.

2. A leveling instrument, comprising an index blade having trunnions and an open-

ing beneath the axis represented by said trunnions, and a pair of tubular balancing sections adapted to be clamped upon opposite sides of said blade in alignment with said opening and to contain a liquid.

3. A leveling instrument, comprising an index blade having trunnions and an opening, and a pair of tubular sections adapted to be screwed together through said opening with said blade clamped between them.

4. In a leveling instrument, a bar having a leveling index member and provided with a socket in one edge at each end thereof, in combination with separate sighting members having stems adapted to be confined within said sockets, one of said members having a straight edge and the other member having a cupped portion with a relatively small sight opening centrally therethrough.

Signed at Cleveland, in the county of Cuyahoga, and State of Ohio, this 28th day of April, 1920.

WILLIAM BERKMAN.
